UNITED STATES PATENT OFFICE.

LOUIS N. LEONARD, OF BUTTE, MONTANA.

WAGON-COVER.

SPECIFICATION forming part of Letters Patent No. 632,578, dated September 5, 1899.

Application filed June 27, 1899. Serial No. 722,061. (No model.)

To all whom it may concern:

Be it known that I, LOUIS N. LEONARD, a citizen of the United States, residing at Butte city, in the county of Silver Bow and State 5 of Montana, have invented certain new and useful Improvements in Wagon-Covers; and I do declare the following to be a full, clear, and exact description of the invention, such as will enable others skilled in the art to which 10 it appertains to make and use the same.

The invention relates to wagons.

The object of the invention is to provide a shield or guard for the body portion of the wagon to protect the goods being hauled from 15 rain, snow, and the like and at the same time afford ready access.

With this object in view the invention consists in certain features of construction and combination of parts, which will be herein- 20 after fully described and claimed.

In the drawings, Figure 1 is a perspective view of a wagon embodying my invention. Fig. 2 is a sectional view through a portion 25 of the side of the wagon, illustrating the engagement of the spring-tongue therewith for the purpose of holding the shield or guard in place against the action of wind, which might get under the shield or guard and tend to lift it.

Like characters of reference indicate like parts in the several views.

1 denotes the wagon-body, having secured to its sides at opposite points brackets 2, provided with perforated ears 3.

4 denotes the rear U-shaped frame, the members of which are provided with lateral studs 5, that project through the apertures in said brackets, one of said studs being formed with a handle 6. 7 denotes an arched bar or rod 30 connected to the sides of said U-shaped frame.

8 denotes the forward U-shaped frame, provided with laterally-projecting studs journaled in the apertures of the brackets. One of said studs terminates in an operating-han- 45 dle 9.

10 denotes an arched bar or rod connected to the forward U-shaped frame.

11 denotes a piece of waterproof material having its opposite ends connected to the U-shaped frames and supported intermediate 50 its ends by the arched bars. This waterproof fabric is of a sufficient width to extend from side to side of the wagon-body.

One of the side pieces of each of the U-shaped frames is provided with a spring- 55 tongue 13, which is adapted to engage the sides of the wagon and form a frictional contact to resist the action of wind should it get under the shield or guard, and thus prevent the same being raised and the contents of the wagon- 60 body exposed to the weather.

When it is desired to remove any of the articles from the wagon, if the article be at the forward end the forward U-shaped frame is elevated and if the article be at the rear end 65 the rear U-shaped frame is elevated, the raising of the two frames being accomplished by operating the handles.

Having thus described the invention, what is claimed, and desired to be secured by Letters 70 Patent, is—

The combination with a wagon-body provided with bearing-brackets, U-shaped frames extending entirely across the wagon-body and having their ends journaled in said 75 brackets, arched bars connecting the sides of each U-shaped frame, a waterproof material having its ends connected to the U-shaped frames and extending entirely across the wagon-body, and spring-tongues carried by 80 the sides of the U-shaped frames for engaging the sides of the wagon-body, substantially as shown and described.

In testimony whereof I have hereunto set my hand in presence of two subscribing witnesses.

LOUIS N. LEONARD.

Witnesses:

MIKE DONLAN,
A. L. SLATER.
